INSTRUMENT FOR BLOOD TRANSFUSION

Rudolf Bucher, Basel, Switzerland, assignor to the
Swiss firm of G. Laubscher & Co., Basel, Switzerland

Application September 4, 1942, Serial No. 457,340
In Switzerland September 20, 1941

2 Claims. (Cl. 128—214)

1

This invention relates to the transfusion of blood plasma, full blood, blood-replacing liquid or serum into human or animal bodies and has for its primary object to provide a new or improved instrument of very simple, light and portable character lending itself to easy manipulation by practitioners, physicians or veterinary surgeons.

Another object of the invention is to provide a new instrument as aforesaid capable of being readily manipulated by the practitioner single-handed, the transfusible liquid being gradually forced out of a flexible receptacle containing the same either by gravity or by a stress exerted with particular advantage through an inflatable actuator such as an air bag arranged inside or outside said receptacle and adapted to progressively contract its wall so as to lessen its volume.

A further object of the invention is to provide a new instrument as aforesaid wherein the means conducting the liquid from its storage receptacle to the transfusion point incorporate a filter whereby said liquid enters the live body in such an optically homogeneous and pure condition as to minimize the risk of embolism or like accidents.

A still further object of the invention is to provide a new instrument as aforesaid wherein the filter has a progressive effect and is so retained in a readily dismountable casing adaptable to the liquid receptacle as to lend itself to easy interchange or cleaning.

With these and such other objects in view as will incidentally appear hereafter, the invention comprises the novel construction and combination of parts that will now be described with reference to the accompanying diagrammatic drawings illustrating three convenient exemplifying embodiments thereof and forming a part of the present disclosure.

In the drawings—

Figure 1 is an elevational view partly broken away of a transfusion instrument representing the first embodiment of the invention.

Figures 2 and 3 are two different views of an instrument similar to the one shown in Figure 1 but provided with a stepped filter and representing the second embodiment of the invention.

Figure 4 is a separate view of a constructional detail of the instrument shown in Figures 2 and 3.

Figures 5 and 6 are respectively an elevational view and a sectional view of a twin rubber bag unit belonging to the instrument shown in Figures 2 and 3.

Figure 7 is an elevational view of a twin rubber bag unit belonging to an instrument repre-

2

senting the third embodiment of the invention.

Like reference characters designate like parts throughout the several views.

As shown in Figure 1, the instrument for the transfusion of blood plasma, full blood and blood-replacing liquid or serum comprises a receptacle constituted by a rubber bag *a* provided with a perforated suspension lug *a*¹ and adapted to receive the transfusible liquid. The mouth of the bag *a* has fitted therein a flanged threaded bushing *b*. Between the annular flange *b*¹ of said bushing and a flat nut *c* are clamped the peripheral edge of the bag mouth and a holding ring *d* provided with a pair of diametrically opposed bails *d*¹, *d*². The threaded bushing *b* is conically splayed out at its outer end to provide a seat into which is tightly fitted a cooperating seat formed on a beaded nipple *k* held against said bushing by a screwed cap *e*. The nipple *k* has an olive-shaped mouthpiece upon which may be frictionally held the one end of a rubber or like hose *f* whose opposite end is connected through a thick walled glass tube *g* and a valve or cock *h* with a transfusion or injection hollow needle *i* interchangeably fitted upon the body of the cock *h* and protected, when not in use, by a suitable hood *i*¹.

It will be understood that by holding the rubber bag *a* at the required height or by hanging it up by means of its suspension lug *a*¹ the blood to be transfused may be caused to flow through the rubber hose *f*, glass tube *g* and needle *i* and that such bag ensures proper uniform and unobstructed outflow of the transfusible liquid following its constantly diminishing capacity, without calling for the intake of atmospheric air.

After removal of the nipple *k* and associated parts, the screwed cap *e* may be replaced by some suitable form of tapped cover (not shown) which can be screwed into tight fitting engagement upon the screw-threaded bushing *b*, thereby permitting the rubber bag *a* to be used not only for immediate transfusion of blood or another transfusible liquid but also for transporting or keeping said blood or liquid stored.

So far as its capacity is concerned, the rubber bag *a* is advantageously so sized as to enable a quantity of transfusible liquid up to 600 cubic centimeters to be either transfused or preserved in stored condition for subsequent use.

As above set forth, an instrument built as above stated presents great advantages for practitioners because it combines the possibility of transfusing blood or blood-replacing liquid such for example as serum without hindrances with

the further possibility of conveniently transporting the same in a non-brittle container and of preserving blood away from outer air access under conditions of utmost safety. Therefore, this improved instrument is particularly well adapted for use either in clinical hospitals or for countryside practitioners or physicians or else for veterinary surgery.

Reference being now made to Figures 2 and 3, it will be seen that the instrument comprises likewise a flexible sealed bag *a* having its mouth provided with a threaded L-shaped bushing *b* upon which may be screwed up for the purpose of transporting the bag filled with liquid a tapped cover *c*¹ (Figure 3). In this embodiment, the instrument also comprises a stepped filter accommodated in a casing *q* and including a stack of three perforated metal disks *q*¹, as shown in Figure 4. Between said disks are interposed filtering layers of a material such for example as silk gauze having different thicknesses, said thicknesses increasing in the downward direction, i. e. towards the lower olive-shaped outlet nipple *q*² of the tapering casing *q*. On the uppermost filtering layer is laid a coarse sieve *q*³ made of wire net or gauze. The superimposed filtering layers are arranged in the cylindrical portion of the casing *q*, the latter surmounting its tapering portion ending in the nipple *q*². Said filtering layers are securely held in proper position in said casing by a wedged in expansion ring *p*. The casing *q* is provided at its upper end with an upstanding rim *v* having an outer flaring wall forming a seat adapted to cooperate with the seat formed by the inner wall of the threaded bushing *b* when the filter unit is connected up to the bag *a*. Said filter unit is securely and removably held in its connected relation to the bag *a* by a screwed cap *m* having an inner shape matching the outer shape of the casing *q* and adapted to be screwed upon the threaded bushing *b*.

Over the olive-shaped nipple *q*² may be frictionally engaged the one end of a rubber hose *f* whose opposite end communicates through a short glass tube *g* with the barrel of a closing off valve or cock *h* to which an injection needle *i* is interchangeably fitted, the tip of said needle being protected when it is not being used by a hood *i*¹.

When carrying out a blood transfusing operation by means of the present instrument, the blood percolates through the several filtering layers and reaches the injection needle *i* in an optically homogeneous coagulate-free condition, thus surely obviating the risk of embolism owing to impurities arising from coagulation.

Reference being now made to Figures 5 and 6, it will be seen that a still designates the rubber bag adapted to receive the transfusible liquid and provided at its upper end with a perforated suspension lug *a*¹ and at its lower end with a 60 tight closure including a tapped cover *c*¹. As above stated and as illustrated in broken lines,

a fitting on a hose connected to an injection needle may be substituted for the tapped cover *c*¹. Inside the bag *a* is provided a smaller air bag *b*³ also made of rubber which can be inflated from a small pump constituted by a hollow rubber ball *c*³ and connected thereto by a hose *c*⁴. By inflating the smaller or inner air bag *b*³, the volume of the larger or outer bag *a* capable of receiving the transfusible liquid is reduced whereby said liquid is forced out and transfused through the injection needle.

In Figure 7 is shown a modification representing a reverse combination of the two bags. The inner bag *m*¹ is adapted to contain the transfusible liquid, while the outer bag *n* can be inflated to so flexibly distort the wall of the bag *m*¹ as to drive the liquid therefrom towards the injecting needle (not shown). Both bags *m*¹ and *n* are advantageously made of rubber.

20 Minor constructional details of the instrument might be changed without departing from the scope of the subjoined claims.

What I claim is:

1. An instrument for the transfusion of liquids, 25 such as blood plasma, whole blood and serum, comprising a primary sealed rubber bag having a mouth, a flanged threaded bushing fitted in said mouth, a secondary sealed rubber bag so associated with the primary bag as to contract the 30 volume of the latter when inflated, means for inflating said secondary bag, said bushing being splayed out to form a seat, a nut screwed on said bushing, a ring clamped together with the peripheral edge of the bag mouth intermediate the 35 bushing flange and said nut, said ring having diametrically opposed bails, a combination filter and outlet nipple having a seat matching the bushing seat to cooperate therewith, a screw cap engageable over said nipple and threadable to said bushing, and means for conducting the liquid from said bag and nipple to the transfusion point.

2. An instrument for the transfusion of liquids, 45 such as blood plasma, whole blood and serum, comprising a primary sealed rubber bag having a mouth, a flanged threaded bushing fitted in said mouth, a secondary sealed rubber bag surrounding the primary bag and so associated therewith as to constrict its volume when inflated, means for inflating said secondary bag, said bushing being splayed out to form a seat, a nut screwed on said bushing, a ring clamped together with the peripheral edge of the bag mouth intermediate the bushing flange and said nut, said ring having diametrically opposed bails, a combination filter and outlet nipple having a seat matching the bushing seat to cooperate therewith, a screw cap engageable over said nipple and threadable to said bushing, and means for conducting the liquid from said bag and nipple to the transfusion point.

RUDOLF BUCHER.
